UNITED STATES PATENT OFFICE.

WILLIAM W. SLOANE, OF CHICAGO, ILLINOIS, ASSIGNOR TO GOODMAN MANUFACTURING COMPANY, OF CHICAGO, ILLINOIS, A CORPORATION OF ILLINOIS.

LOCOMOTIVE.

Application filed January 23, 1922, Serial No. 531,074. Renewed March 19, 1923.

To all whom it may concern:

Be it known that I, WILLIAM W. SLOANE, a citizen of the United States, residing at Chicago, in the county of Cook and State of Illinois, have invented Improvements in Locomotives, of which the following is a specification.

This invention relates to improvements in locomotives or trucks and has for its principal object to provide an improved construction affording relative flexibility of the supporting wheels and axles so as to readily follow uneven track.

In locomotives of the usual type, the axles are supported in suitable axle boxes mounted on vertically disposed guides on the locomotive frame and having springs interposed between each axle box and the frame. Such a construction allows the end of the axle to move vertically a limited distance depending upon the resiliency of the springs. In the present invention, I provide means affording greater flexibility of movement of the axle comprising an equalizing device in which the opposite ends of a single axle are each connected to a longitudinally disposed bar pivotally mounted on the frame and movable in a vertical plane. The free ends of these bars are connected by suitable links to a torsion bar extending transversely of the frame and pivoted thereon. By means of this arrangement the axle is permitted to swing in a vertical plane independent of the resiliency of the springs.

The invention consists in the combination, construction and arrangement of parts as will hereinafter be described in connection with the accompanying drawings and more particularly defined in the appended claims.

In the drawings,

Figure 1 is a fragmentary top plan view of a locomotive showing one of the axles thereof provided with an equalizing device constructed in accordance with my invention.

Fig. 2 is a side view of a locomotive with portions of the supporting wheel and one side of the frame broken away to show the construction and arrangement of the equalizing device.

In the drawings, one embodiment of my invention is illustrated, as applied to a locomotive frame having side plates 2, 2, an axle 3 and supporting wheels 4, 4. Suitable journal boxes 5, 5, are mounted adjacent opposite ends of the axles and are movable ver-

tically between oppositely disposed guide plates 6, 6, of a pedestal 7 which may be of any suitable construction. The equalizing device comprises a pair of longitudinally disposed supporting bars 8 and 9 pivotally mounted on opposite sides of the locomotive frame on pivotal joints 8^a and 9^a respectively. One of the supporting bars 8 is preferably shorter than the supporting bar 9 as shown. Springs 10, 10, which may be of the usual helical type or its equivalent, are interposed between each of the axle boxes 5, 5, and stirrups 8^b and 9^b located intermediate the ends of supporting bars 8 and 9 respectively. In the preferred form shown, each of said stirrups projects downwardly and outwardly into supporting position above its respective spring 10, which is movably mounted between the guide plates 6, 6, of the pedestal 7 as already described. This arrangement of the stirrups and springs may be varied, as desired, depending upon the type of springs employed, and variations in design of the frame and axle. The free ends of supporting bars 8 and 9 are operatively connected by means of a transversely disposed torsion bar 11. The supporting bar 8, which is the shorter of the two supporting bars, is connected to a crank arm 12 by means of a pivotal link 13. Said arm 12 is rigidly mounted on the torsion bar 11 and extends longitudinally therefrom toward the axle 3. An arm 14 is rigidly mounted on the opposite end of the torsion member 11 and extends longitudinally in a direction opposed to the arm 12. Arm 9 is pivotally connected to the arm 14 by a pivotal link 15. The arrangement is such that any pivotal movement of one of the supporting arms such as the arm 8, in one direction will cause rotation of the torsion member 11 and a corresponding movement of arm 9 in the opposite direction. Any vertical displacement of one end of the axle will therefore cause a corresponding displacement of the opposite end of the axle in a reverse direction. It will thus be seen that when the locomotive is moving over uneven track, the axle is free to swing a limited distance in a transverse plane irrespective of the resiliency of the springs.

In applying my invention to a locomotive of the two axle type, it is preferable to mount one of the axles in the usual manner, that is to say, without an equalizing device,

so as to afford the desired stability to the frame, while the other supporting axle is mounted as above described so as to afford a wide range of flexibility with respect to the frame and the one stabilizing axle connected therewith. By means of this arrangement, the load is maintained evenly on all of the supporting wheels while moving over uneven track. In a similar manner, when applied to a three axle locomotive, two of the axles only are provided with transverse equalizing devices.

Although I have shown and described one form in which my invention may be embodied, it will be understood that many other means may be employed for accomplishing the same results, without departing from the spirit and scope of my invention. I do not therefore wish to be understood as limiting myself to the specific construction or use illustrated herein excepting as specifically limited in the appended claims.

I claim as my invention:

1. In a car, a frame, an axle movable in a substantially vertical plane respective to said frame, and an equalizing device comprising a pair of longitudinally extending bars each pivotally mounted on the frame adjacent opposite ends of said axle in supporting engagement therewith, and means operatively connecting said bars together, including a transversely disposed torsion member pivotally mounted on the frame.
2. In a car, a frame, an axle movable in

a substantially vertical plane respective to said frame, and an equalizing device comprising a pair of longitudinally extending bars each pivotally mounted on the frame adjacent opposite ends of said axle in supporting engagement therewith, a transversely disposed torsion member pivotally mounted on the frame, and means coacting between each of said bars and said torsion member whereby vertical movement of one end of said axle in one direction is transmitted through the medium of said torsion member and said bars and causes a corresponding movement of the other end of said axle in the opposite direction, and vice versa.

3. In a car, a frame, an axle movable in a substantially vertical plane respective to said frame, a pair of longitudinally extending bars each pivotally mounted on the frame adjacent opposite ends of said axle in supporting engagement therewith, a transversely disposed torsion member rotatably mounted on said frame, a longitudinally disposed rigid arm on said torsion member extending in one direction and having operative connection with one of said bars, and an oppositely disposed arm having operative connection with the other of said bars.

Signed at Chicago, in the county of Cook and State of Illinois, this twenty-first day of January, 1922.

WILLIAM W. SLOANE.
